(57) **CLAIM**

The ornamental design for a dispensing carton, as shown and described.

DESCRIPTION

FIG. 1 is a perspective view of a dispensing carton according to a first embodiment of the disclosure.

FIG. 2 is a front elevation view of the dispensing carton of FIG. 1, the back elevation, right elevation, and left elevation views are identical to FIG. 2.

FIG. 3 is a top plan view of the dispensing carton of FIG. 1.

FIG. 4 is a bottom plan view of the dispensing carton of FIG. 1.

FIG. 5 is a perspective view of a dispensing carton according to a second embodiment of the disclosure.

FIG. 6 is a front elevation view of the dispensing carton of FIG. 5, the back elevation, right elevation, and left elevation views are identical to FIG. 6.

FIG. 7 is a top plan view of the dispensing carton of FIG. 5.

FIG. 8 is a bottom plan view of the dispensing carton of FIG. 5.

FIG. 9 is a plan view of FIG. 5 shown unfolded; and, FIG. 10 is a plan view of FIG. 1 shown unfolded.

The broken lines in the drawings depict environmental subject matter and form no part of the claimed design. The broken lines in the form of an alternating series of relatively short dashes and relatively long dashes that are immediately adjacent to the shaded area represent the bounds of the claimed design.
